United States Patent Office

Des. 188,456
Patented July 26, 1960

188,456

TRACTOR

Henry Dreyfuss, South Pasadena, and William F. H. Purcell, Pasadena, Calif., assignors to Deere & Company, Moline, Ill., a corporation of Delaware

Filed July 16, 1959, Ser. No. 56,797

Term of patent 14 years

(Cl. D14—3)

FIG. 1

Des. 188,456

PAGE 2

FIG. 2

Des. 188,456

PAGE 3

FIG. 4

Fig. 1 is a three-quarter perspective as seen from the left front of the tractor embodying our new design.

Fig. 2 is a similar perspective, but taken from the opposite side thereof.

Fig. 3 is a three-quarter perspective as seen from the left rear thereof.

Fig. 4 is a front perspective thereof.

The essential features of our design reside in those portions shown in full lines.

We claim:

The ornamental design for a tractor, substantially as shown and described.
